METHOD AND APPARATUS FOR OPENING
FIBROUS AGGLOMERATIONSJoseph H. Zettel, Martinsville, N. J., assignor to
Johns-Manville Corporation, New York, N. Y.,
a corporation of New York

Application July 26, 1947, Serial No. 763,816

9 Claims. (Cl. 154—28)

1

The instant invention relates to a method and apparatus for opening and tufting fibrous agglomerations or nodules and, more particularly, is directed to the opening and fluffing of nodules of mineral wool and like fibrous materials. The opened, fluffed nodules find a principal field of use as a component material for mineral wool blankets or blocks but they may be employed for other purposes. As the term "mineral wool" is employed herein it is intended to include fibers formed from rock, slag, glass, mixtures thereof, and like mineral materials subject to conversion into fibrous form.

Relatively rigid mineral wool blocks and blankets for insulation and other purposes have been made in a number of ways, and recent developments in the construction of improved materials of this type involve the utilization of the mineral wool in nodular or agglomerate form, the nodules containing a binding material. In the formation of the product the nodules are distributed on a conveyor or other receiving surface to form a layer, and this layer is compressed and the binder then activated and set whereby a unitary product is obtained in which the binder serves to secure the nodules into coherent sheet form, as well as to bond the fibers in the individual nodules. The principal object of the instant invention is the provision of a method and apparatus for opening and fluffing nodules whereby, when used in such method, an improved interlocking between the fibers of adjacent nodules and greater homogeneity of the product are obtained. More specifically an object of the invention is the provision of a method and apparatus for subjecting fibrous nodules containing a distributed binder or other treating material to a rubbing, rolling and shearing action to open, tuft or fluff them and also to secure a more thorough distribution of the treating material over the fibers.

Another object of the invention is the provision of an apparatus for the purposes mentioned above, the apparatus including a cylindrical brush and a member adjacent the brush defining therewith the confined zone through which the nodules are carried by rotation of the brush and subjected during their passage to a shearing, rolling and tearing action.

A still further object of the invention is the provision of a method and apparatus of the type referred to above which performs the additional function of distributing the opened nodules on a conveyor or other receiving surface to build up a substantially uniform thickness layer.

My invention will be more fully understood and further objects and advantages thereof will become apparent when reference is made to the following more detailed description of the preferred embodiment of the invention and to the accompanying drawings in which:

2

Fig. 1 is a diagrammatic, side elevational view of an apparatus in accordance with the invention and for carrying out the method thereof;

Fig. 2 is an end elevational view of the apparatus;

Fig. 3 is a sectional view taken on the line 3—3 of Fig. 2; and,

Fig. 4 is a partial sectional view illustrating a modification of the apparatus.

Referring now to the drawings, there is diagrammatically shown an apparatus embodying the invention and for carrying out the method thereof, the apparatus including a cylindrical brush 10 carried by a shaft 12 supported in suitable bearings 14 mounted on frame elements 16 of the machine. The shaft and roll are adapted to be driven in the direction indicated by the arrows in Figs. 1 and 3 by any suitable means, such as pulley 18, keyed to an extending end of the shaft and operatively connected to a motor or other drive device (not shown) by a belt or chain 20. The brush is preferably relatively stiff and, for this purpose has wire bristles which also have the advantage of resisting the abrasive action of the mineral wool. The brush may be of any standard construction and may include a core or mandrel section 22 in which the bristles are secured.

Referring now particularly to Fig. 3, a member or plate 24 of semi-cylindrical contour, at least on its inner face, suitably an arcuate section of steel pipe, is mounted adjacent to the brush to define a restricted zone between it and the periphery of the brush. In the preferred embodiment the zone is of substantially uniform depth throughout, that is, the inner surface of member 24 is concentric to the brush. The depth of the zone will depend upon the particular type of agglomerations or nodules to be treated but for purposes of example it may be noted that for nodules or tufts of mineral wool, it has been found that a depth of about $\frac{1}{2}$ " to 1" is satisfactory. The arcuate extent of member 24 may also vary within reasonable limits. A half pipe section of a diameter 1" to 2" greater than the diameter of the brush and mounted concentrically to the brush has been found to provide good results. The ends of zone 26 may be closed as by end plates 28 or, if this section of the machine is enclosed, the side walls of the enclosure may serve this purpose.

At or adjacent the forward end of member 24 a baffle or lip 29 is provided, the lip extending the full length of the brush and projecting approximately half the depth of the restricted zone from member 24. For example, where the depth of zone 26 is 1" the lip may be a steel bar $\frac{1}{2}$ " in thickness welded to the inner surface of member 24 at its forward end. A discharge port 30 is defined between the lip 29 and the brush and at

this location there may be an adjustably mounted deflector plate 32 adapted to control or direct the direction of discharge of the nodules issuing from between the brush and member 24. To permit the required adjustment, deflector plate 32 is preferably hinged as illustrated at 34 to lip 29 and a device is provided to secure the plate in any adjusted position. This may take the form of an arm 36 having an elongated, arcuate slot 38 to receive a thumb screw or other securing device 40 threaded into end plate 28 or other fixed element of the apparatus. It will be appreciated that any suitable adjusting device can be substituted for that shown.

The device for delivering the nodules to the confined zone 26 may be of any conventional type but in the form shown consists of an inclined chute 42 which permits the nodules to move by gravity into the zone. A receiving surface 44, usually a continuously traveling conveyor, is mounted below the apparatus to receive material discharged through port 30.

In the operation of the apparatus described above and in carrying out the method of the invention, nodules or agglomerations of mineral wool or other fibrous materials, preferably carrying a finely-divided or powdered treating material such as a powdered, phenol-formaldehyde resin binder intermixed therein, are deposited in trough 42 and discharged therefrom against brush roll 10 at the entrance end of zone 26 and are carried into said zone by rotation of the brush roll. The brush roll is driven in a direction (counter-clockwise in the construction shown) to carry the nodules into and through restricted zone 26. As the nodules pass through this zone they are subjected to a rolling, tearing and shearing action which tends to tuft or fluff them and open them. At the same time the shearing and tearing action serves to smear the binder particles on the fibers and to provide a better and more uniform distribution of the binder throughout the nodules. These effects on the nodules are accentuated by the action of baffle or lip 29. That is, as the material passes between the brush and member 24 a portion of it, and particularly small fibrous bunches and relatively individualized fibers and unfiberized material separated from the nodules build up behind the lip for a substantial distance to provide a rough surfaced body across which the nodules are drawn or raked in their passage to discharge port 30. The material piled up behind the lip will be gradually drawn through the port by the passage of the nodules over it but, inasmuch as it is immediately replaced by additional material, the rough surface is constantly maintained.

In some instances, particularly where tough fibrous material or tightly interlocked fibrous bunches or nodules are to be opened, it may be advisable to provide a roughened or toothed surface on the inner surface of plate 24. For example, as illustrated in Fig. 4, a material such as card clothing 46 may be used, the clothing being secured to the inner surface of the plate in any suitable manner. Enhanced shearing and tearing of the nodules is obtained by this modification.

The speed of the brush roll may vary substantially without seriously affecting the efficient operation of the apparatus. For example, speeds between 300 and 1700 R. P. M. for a 12" diameter brush have been found operable, although relatively lower speeds, say between 300 and 700

R. P. M., are preferred to avoid excessive dustiness while still securing maximum effectiveness.

The opened nodules are discharged through port 30 with the forward impetus imparted to them by the brush roll. The normal trajectory of the nodules leaving the discharge port may be all that is necessary to provide satisfactory distribution for some purposes and, in such case, deflector plate 32 is not required. However, where a more positive control is desired, the deflector plate is adjusted to the angle required to direct the nodules through a trajectory which will insure a given distribution on receiving surface 44.

The method and apparatus described above have been found particularly advantageous for use in connection with the production of blocks or blankets by the general process referred to above. When employed therein it has been found that superior products are obtained, even though the binder is originally imperfectly distributed in the fibrous nodules due, both to spreading of the binder on the fibers and the fluffing of the nodules. In the product, the projecting fibers of the tufted and fluffed nodules interlock the nodules and, together with the improved distribution of the binder, result in a greatly increased modulus of rupture. As previously stated, although the invention is specially adapted for use in such process, it also may be incorporated in other processes where opened, fluffed nodules or agglomerations are desired. Also its use is not limited to the opening or fluffing of mineral wool nodules as it is applicable to other fibrous materials.

Having thus described my invention in rather full detail, it will be understood that these details need not be strictly adhered to but that various changes and modifications may suggest themselves to one skilled in the art, all falling within the scope of the invention as defined by the subjoined claims.

What I claim is:

1. A method of opening and tufting agglomerations of fibrous material comprising discharging the agglomerations between a rotary brush and an obstructed surface to subject the agglomerations therebetween to a rolling, shearing and tearing action.
2. A method of opening and tufting mineral wool nodules and of distributing a powdered binder therein comprising delivering the nodules to a restricted zone between a rotating brush and a semi-cylindrical surface generally concentric to the brush and including a roughened section to subject the nodules therebetween to a rolling, shearing and tearing action whereby the nodules are opened and the treating material is spread over the fibers thereof.
3. A method of opening and tufting mineral wool nodules and of distributing the open nodules on a receiving surface comprising delivering the nodules to a confined zone between a rotating brush and a surface including a roughened section to subject the nodules in said zone to a rolling, shearing and tearing action whereby the nodules are opened and tufted, and discharging the opened nodules from said zone under the impetus of said rotating brush to distribute the nodules on a receiving surface.
4. A method of opening and tufting mineral wool nodules and of distributing the nodules on a receiving surface comprising delivering the nodules carrying a powdered binder to a restricted zone between a rotating brush and a semi-cylindrical

drical surface generally concentric to the brush and having in part a roughened surface composed of the material of the nodules to subject the nodules in said zone to a rolling, shearing and tearing action whereby the nodules are opened and the treating material is spread over the fibers, and discharging the opened nodules from said zone under the impetus of said rotating brush to distribute them on a receiving surface.

5. A method of opening and tufting agglomerations of fibrous material comprising discharging the agglomerations between a rotary brush and a toothed surface to subject the agglomerations therebetween to a rolling, shearing and tearing action.

6. An apparatus for opening and tufting fibrous nodules comprising a cylindrical continuous brush mounted for rotation, a semi-cylindrical member adjacent said brush and spaced substantially uniformly therefrom to define a restricted zone for the agglomerations or nodules, a forward end on said member, a baffle positioned adjacent said forward end within said zone and extending toward said brush to define a discharge port, means for delivering nodules to the zone and means for rotating the brush.

7. An apparatus for opening and tufting fibrous nodules comprising a cylindrical continuous brush mounted for rotation, a semi-cylindrical member adjacent said brush and spaced substantially uniformly from the periphery thereof to define an arcuate, restricted zone, a forward end on said member, a baffle positioned adjacent said forward end within said zone and extending toward said brush to define a discharge port, means for delivering nodules to the zone and means for rotating the brush.

8. An apparatus for opening and tufting fibrous nodules comprising a cylindrical continuous brush mounted for rotation, a semi-cylindrical member adjacent said brush and spaced therefrom to define a restricted zone, a forward end on said member, a baffle adjacent said forward end and extending toward said brush to define a discharge port, means for delivering fibrous nodules to the

5 zone adjacent the end thereof opposite said port, means for rotating said brush, and a deflector plate adjustably mounted adjacent said discharge port to control the distribution of the nodules discharged through said port.

10 9. An apparatus for opening and tufting fibrous nodules comprising a cylindrical continuous brush mounted for rotation, a semi-cylindrical member adjacent said brush and spaced therefrom to define a restricted zone, a forward end on said member, a baffle adjacent said forward end and extending toward said brush to define a discharge port, means for delivering fibrous nodules to the zone adjacent the end thereof opposite said port, means for rotating said brush, a deflector plate hingedly connected to said semi-cylindrical member adjacent the discharge port to control the discharge of the nodules discharged through said port, and means for adjustably positioning said deflector plate.
